UNITED STATES PATENT OFFICE.

JACQUES H. LEFF AND ROBERT H. SPIRA, OF NEW YORK, N. Y.

DESIGN FOR A BADGE.

52,140.

Specification for Design.

Patented July 2, 1918.

Application filed March 12, 1918. Serial No. 222,041. Term of patent 3½ years.

To all whom it may concern:

Be it known that we, JACQUES H. LEFF and ROBERT H. SPIRA, both citizens of the United States, and residents of New York city, borough of Manhattan, in the county and State of New York, have invented a new, original, and ornamental Design for Badges, of which the following is a specification, reference being had to the accompanying drawing, forming part thereof.

The figure is a plan view of a badge showing our new design.

We claim:

The ornamental design for a badge, as shown.

JACQUES H. LEFF.
ROBERT H. SPIRA.
